Ms. 380

Samuel W Gibbs of Albany Newyork,
(Assignor to Jagger, Treadwell & Perry)
Letters patent No 380. Dated June 10th 1851

The Schedule referred to in these Letters Patent and making part of the
same.

To whom it may concern

Be it known that I Samuel W Gibbs of the City of Albany and
State of Newyork have produced a new and original ornamental De-
sign for the Front plate, side plate, & doors of a Cooking stove and I
hereby declare the accompanying and annexed drawings forming part
of this specification to be full and accurate delineations of the said
plates, doors, and their ornaments, the side plate with its doors and, the
half front plate with its door represented, being symmetrically similar
to a side plate and door, forming the left side of a stove, and the right hand
portion of the front plate and door forming with the part represented the
entire front of the stove.

Yours - I

2

Dec. 380

chain as my production and desire to secure by Letters Patent is the combination and arrangement of ornamental forms and figures represented in the annexed drawings forming the ornamental designs for front & side plates of a cooking stove with the doors thereto belonging.
